DOOR FASTENER

Samuel P. Hull, Yonkers, N. Y., assignor to Railroad Accessories Corporation, New York, N. Y., a corporation of New York

Original application February 20, 1935, Serial No. 7,323. Divided and this application April 2, 1937, Serial No. 134,492

4 Claims. (Cl. 70—2)

This invention relates to fastening devices, especially to locks, and more particularly to a hasp-lock of the type adapted to secure swinging doors in closed position relatively to the door-frame.

An object of the invention is to provide improved hasp-lock fastening devices for use as standard equipment upon a series of cabinets installed along the right-of-way of a railroad and intended for containing operating relays, tools and supplies, etc.

It is desirable that such cabinets be secured against access to their interior by unauthorized persons, but readily accessible to numerous individual operatives each provided with a master key adapted to lock and unlock all the "padlocks" by which term the fastening devices for such cabinets are known generally to such operators, whether or not they include a conventional padlock or any suitable locking device not operable by hand without some form of key or actuating member.

Other objects and advantages will appear as the description of the particular physical embodiment selected to illustrate the invention progresses, and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

Figure 1 is a view in horizontal section of a hasp-lock fastening device, in the construction of which the invention has been embodied, and shown in position upon the associated parts of a cabinet to which it is applied including portions of the door-frame and swinging door; Fig. 2 is a front elevational view of the device as shown by Fig. 1, with some parts broken away to more clearly show the construction; Fig. 3 is a view in side elevation of the device shown in Figs. 1 and 2; Fig. 4 is a detail view like Fig. 3, but showing the keeper member separately; Fig. 5 is a plan view of the mounting pivot member for the hasp, taken separately; Fig. 6 is a fragmentary, detail view like Fig. 1, but showing a modification.

In the now preferred embodiment of the invention selected for illustration, and referring first to Figs. 1 to 5 inclusive, the reference character 11 designates generally a swinging door, such as the door of a cabinet of the type

known as a "relay cabinet", being one of a series installed along the right-of-way of a railroad, the door frame being designated generally as 12, while 13 designates an inner panel, adapted to be engaged with a rabbeted portion 14 of the upright free edge of the door, which it is desired to bring into firm, snug contact therewith.

In pursuance of the invention, I provide a hasp lock fastening comprising a hasp-element 15 mounted pivotally near the upright edge of the door, and carried bodily by the door, being also adapted to swing about its pivot into juxtaposition with a keeper element 16 when the door is closed.

The hasp element includes a mounting plate or member 17 of a size and shape suitable to fit within a yoke 18 formed at the pivot end of the hasp member, this mounting plate being secured to the door by a bolt 19 transfixing the door and mounting plate, the latter having an opening 20 through which the bolt passes, and wings 21 so spaced as to accommodate the squared head 22 of the bolt, preventing it from being turned from the outside of the door. The inside end of the bolt 23 is provided with the usual nut and washer securement.

The outer faces of the wings and adjoining part of the mounting plate 17 are shown as provided with open sockets 24 to receive the pivot posts 25 with which the yoke 18 is furnished, and spurs 26 may be provided to prevent turning movements of the mounting plate, so that when the hasp member 15 is swung out of engagement with the keeper 16 it will be maintained in its horizontal plane.

The shank 27 of the hasp member may desirably be trough-shaped in cross-section for the sake of strength with lightness and at its free end the hasp has a head 28 in which is fitted a set-screw 29 which is provided with a part 30 designed to serve as means to permit the screw to be operated readily by hand, for locking purposes.

In the form of construction shown in Figs. 1 to 4 inclusive, the manual operating means takes the form of a wing-nut, fixed by a pin 31 to the shank of set-screw 29, and either wing, or both wings 32 of this nut may be desirably pierced, as at 33, to receive the loop 34 of a conventional padlock 35.

When the padlock is in place, its loop 34 hangs between the flanges 36 each side of the trough shaped portion 27 of the hasp member, so that the wing nut cannot be turned until 55

an operator provided with a key opens and removes the lock 35.

The keeper element 16 is of improved construction especially designed to cooperate efficiently with the hasp element, to hold the latter in its adjusted position securing the door 11 snugly against the frame members 12 and 13.

For this purpose, the keeper element has a ridge 37 around the seat 38 against which the nose of the set-screw 29 bears, and this ridge prevents any chance of a lateral escape by slipping of the set screw when the latter has been firmly driven home.

The preferred shape and extent of this ridge 37 is best shown in Fig. 4, from which it will be clear that the part 37 constitutes a substantial barrier against the introduction of a tool, such as a screw-driver, in an effort to reach and displace the set screw 29.

Such tampering is further prevented by a high wall part 39 of semicircular contour, reinforced at its rear by a buttress 40. The keeper also is made with a stout L-shaped base having a lug 41 secured to the door-jamb 12 by screw 42 which is protected by the hasp member 27 from being withdrawn when the door is closed; and the base plate lug 43 may be desirably secured firmly by a square headed wood screw 44, or other suitable securing, according to the character of the cabinet to which the device is applied.

It will be readily understood from the foregoing disclosure that the hasp-lock-fastening device is very strong, sturdy, economical to manufacture and to install; cannot be readily removed, and is proof against tampering unless the latter be studied and carried to a destructive extent, and even such malicious interference will be at least discouraged if not prevented to a large extent.

The same is true of the modification illustrated in Fig. 6, which is merely illustrative of a considerable range of diverse forms in which the invention may be embodied by those skilled in the art, upon the basis of the disclosure found herein.

Fig. 6 shows a set screw 45 which has a non-circular head 46 adapted to receive a removable operating key 47 in place of the wing nut 30 shown in Fig. 1, but otherwise operating in the same manner.

It will be noted that the head of the hasp element is provided at 48 with a protective wall which extends to a distance sufficient to prevent easy operation of the set-screw when the key 47 is not in place. This form of device is available for many applications of the device where the risk of interference is less than warrants the provision of a conventional padlock, and in fact the form of lock shown in Fig. 6 may be, and is, regarded as a "padlock" in the terminology of railroad equipment.

Although I have particularly described one particular physical embodiment of my invention and explained the operation, construction and principle thereof, nevertheless, I desire to have it understood that the form selected is merely illustrative, but does not exhaust the

possible physical embodiments of the idea of means underlying my invention.

This application is a division of my prior application Serial No. 7,323, filed February 20, 1935, for Door fastener, now Patent No. 2,077,626, granted April 20, 1937.

What I claim as new and desire to secure by Letters Patent of the United States, is:

1. A fastening device of the nature of a hasp-lock for securing a swinging door to its frame in closed position, said device comprising a hasp-element including a hasp member, and a pivot-plate member by which said hasp element may be mounted pivotally upon said door; a keeper element adapted to be secured to said door-frame in the path of movement of said hasp around its pivot; and a locking means, including a screw device carried by the free end of said hasp member, and means by which said screw device may be operated manually to cause firm engagement of said hasp with said keeper and snug engagement of said door with its frame, said keeper element formed with a wall obstructing access to the contacting end of said screw device. 15

2. A hasp-lock-fastener comprising the elements combined and cooperating as set forth in claim 1, and further characterized by the co-operative arrangement of said screw-device and keeper to draw said door lengthwise to bring its upright free edge into abutting engagement 20 with the door jamb. 25

3. A fastening device of the nature of a hasp lock for securing a swinging door to its frame in closed position, said device comprising a hasp-element including a hasp member and a pivot-plate member by which said hasp element may be mounted pivotally upon said door; a keeper element adapted to be secured to said door-frame in the path of movement of said hasp around its pivot; and a locking means including a screw device carried by the free end of said hasp member, and a wing-nut by which said screw device may be operated manually to cause snug engagement of said hasp with said keeper and of said door with its frame, and a padlock adapted 40 to engage said wing-nut and be engaged with said hasp element, to hold said screw device against unauthorized operation, said keeper element formed with a wall obstructing access to the contacting end of said screw device. 50

4. A fastening device of the nature of a hasp-lock for securing a swinging door to its frame in closed position, said device comprising a hasp-element including a hasp member and a pivot-plate member by which said hasp element may be mounted upon said door; a keeper element adapted to be secured to said door-frame in the path of movement of said hasp around its pivot; a locking means including a set-screw carried by the free end of said hasp, and operable manually to cause snug engagement of said hasp with said keeper; said device being characterized by having said keeper and hasp respectively provided with circular barriers disposed co-axially around said screw to prevent tampering therewith. 60 65
